UNITED STATES PATENT OFFICE.

ARTHUR F. PITKIN, OF SCHENECTADY, NEW YORK.

MANUFACTURE OF STEAM-BOILER STAY BOLTS.

Application filed July 18, 1922. Serial No. 576,027.

My invention relates to steam boiler stay bolts of the articulated or so-called "flexible" type, and its object is to provide a means and method whereby stay bolts of such type, having a socketed end or ends, may be inexpensively manufactured, of sections sufficiently strong to safely resist the strains imposed upon them in their pressure upon inner and outer sheets of steam boilers.

10 The improvement claimed is hereinafter fully set forth.

In the accompanying drawings: Figure 1 is a view, in elevation, of one section of an impressioned die block adapted to the practice of my invention, with the socket portion of the material operated on shown in section at the conclusion of each operation; Fig. 2, a similar view of a plunger die block, with portions of the plungers shown in section; Figs. 3, 4 and 5, longitudinal central sections through the socket end of the forging, at the conclusions of the first, second, and third operations respectively; Fig. 6, a similar section showing the staybolt articulated to a ball member by which it is to be connected to a boiler sheet; and, Fig. 7, a view, in perspective, illustrating the relation of the impressioned and the plunger die blocks.

15 For the practice of my invention, which is herein exemplified as applied in the manufacture of articulated stay bolts having a socket on one end only, although it is equally and similarly applicable in that of stay bolts having a socket on each end, I provide an impressioned die block which comprises two counterpart sections, A and A', in the meeting faces of which there are formed three impressions or recesses, a, b and c, the rear portions of which, when the counterparts are brought into contact, are of cylindrical section, corresponding to that of the body of the bolt which is to be manufactured. The adjoining portions, a', b', and c', of the impressions, are of greater diameter, and of 20 section corresponding to the periphery of the socket which is to be formed on the bolt, and the extreme front portions, b² and c³, of the impressions, b and c, are of cylindrical section and of greater diameter than the portions, b' and c'.

25 To operate in connection with the impression die block, there is also provided a plunger die block, B, the face of which carries plungers, d' and d², of diameters corresponding with the portions, a' and b², of the recesses of the impression die blocks, A,

and a plunger, d³, of diameter corresponding substantially with that of the portion, c³. A central projection, d⁴, of smaller diameter, and an annular groove, d⁵, surrounding the bottom of said projection, are also formed on the plunger, d³. For application in connection with the cylindrical end portion, c³, of the impression, as hereinafter described, there is also provided a stout metal ring, A². 30

35 In the practice of the method of my invention, which is conducted in a forging machine of any suitable known construction, which does not, in and of itself, form part of my present invention, and is not, therefore, herein set forth, one of the sections, as A, of the impression die block, is moved sufficiently away from the other section, as A', to permit the insertion from the rear, in the impression, a, of a heated bar stock of 40 material of circular or other suitable transverse section, which is allowed to project from the front of the impression, a, sufficiently far that when the sections, A and A', are brought together, and the plunger die block, B, is forced forward by the action of the forging machine, the plunger, d³, of said block, will upset or force inwardly the material of the bar stock, so as to fill the 45 space before it in the portion, a', of the impression, a, the stock being securely clamped between the sections.

50 The end of the stock on which the plunger, d³, acts, having been upset to the form shown in the impression, a', in Fig. 1, the bar stock is next inserted in the impression, b, and by the action of the forging machine, is cupped out and brought to the form shown in the portion, b', of said impression by the plunger, d⁴, of the plunger die block, B. In the performance of this operation, 55 there is found to be a small "flash" or protruding peripheral flange, 1^a, produced on the socket portion, by the metal squeezing out between the die blocks, to remove which 60 the bar stock is placed in the impression, c, in which the ring, A', is inserted, and by another forward movement of the plunger die block, said "flash" is cut off, thereby completing the formation of the socket. 65

70 The stay bolt thus manufactured has a body, 1, and an integral socket, 1^a, and is articulated to the ball, 2^b, of the plug member by which its socket end is connected to a boiler sheet, by inserting the ball in the 75 socket, and forcing inwardly, around the ball, the outwardly flaring end of the socket,

2

thereby forming a bearing face on the socket for the ball, and holding the ball in the socket, as shown in Fig. 6. The socket is preferably made of such depths as to 5 present a space, 1° , within it between the ball and the socket, which allows a limited range of relative longitudinal movement, as set forth in an application for Letters Patent filed by me under date of October 22, 1921, 10 Serial No. 509,551. The exterior surface of the socket is also caused to be essentially cylindrical, and concentric with the axial line of the body, 1, of the stay bolt thereby providing a bearing socket, 1° , which is of 15 greater thickness at its outer end than on the remainder of its wall, and, by being so thickened, is strengthened to such an extent as to effectually resist any tendency for the bolt to be pulled out of the socket, when in 20 service, by the turning outwardly of the end portion, under strain.

I claim as my invention, and desire to secure by Letters Patent:

The method of forming stay bolts, having a socket at one end for the reception of the 25 rounded head of a companion member, which comprises the following steps: heating a rod to forging temperature; confining the rod in a die cavity, having a constricted portion and an enlarged portion; expanding 30 one end of the rod in the enlarged portion by the pressure of a plunger; confining the rod in a second die cavity; applying pressure to the expanded end of the rod to form a socket therein, with the mouth of said 35 socket thicker than the rest of the wall and curved in cross section; confining the rod in a third die cavity, and cutting off any fin formed around the thickened mouth of the socket.

ARTHUR F. PITKIN.
